UNITED STATES PATENT OFFICE

FRANK JARDINE AND JAMES COOPER, OF CLEVELAND, OHIO, ASSIGNEES, BY MESNE ASSIGNMENTS, TO THE CLEVELAND TRUST COMPANY, OF CLEVELAND, OHIO, A CORPORATION OF OHIO, AS TRUSTEE

PISTON

Application filed January 6, 1926. Serial No. 79,651.

This invention relates to pistons for internal combustion engines or the like, and more particularly to pistons made of some metal having a relatively high co-efficient of expansion such as aluminum or aluminum alloy, or the like, to be used in a cylinder made of a material having a relatively low co-efficient of expansion such as cast iron or the like.

10 The present invention is an improvement over the piston claimed in our co-pending application Serial No. 79,800, filed January 7, 1926, and embodies the invention claimed broadly in the co-pending application of 15 Frank Jardine, Serial No. 47,214, filed July 31, 1925.

It is well known that such pistons possess many desirable qualities such as lightness, high heat conductivity and the like, but since 20 the co-efficient of expansion due to heat of such materials differs from that of the cylinders in which they operate, difficulties and disadvantages are encountered at various 25 temperatures, for example, pistons that will not slap when cold will stick when hot, and vice versa.

The principal object of our invention is to provide a piston made of aluminum, aluminum alloy, or the like, which can be fitted 30 with a very small clearance when installed and which clearance will be substantially maintained throughout the temperature ranges met in practice, without slapping, binding or scoring of the cylinder or undue 35 wear on the piston itself.

These and other objects of our invention as well as the invention itself will be better 40 understood from a description of one or more structures embodying the invention.

In the drawings forming a part of this specification—

Fig. 1 is a side elevation of a piston embodying our invention;

45 Fig. 2 is a section thereof along the line 2—2 of Fig. 1;

Fig. 3 is a bottom plan view thereof;

Fig. 4 is an elevation of the member A hereinafter to be particularly described;

50 Figs. 5, 6 and 8 are views of a second pis-

ton embodying our invention corresponding to Figs. 1, 2 and 4; and

Fig. 7 is a transverse sectional view taken on line 7—7 of Fig. 5.

We will refer first to the embodiment illustrated in Figs. 1 to 4, inclusive. The head of the piston is shown at 9 and consists of the top 10 and side walls 11 grooved at 12 for the piston rings. The walls 11 are shown as cylindrical. As many grooves 12 as desired may be used. The piston skirt is shown generally at 13 and comprises thrust or wear face parts 14 and 15. The part 14 is connected directly to the head,—preferably it is integral with the head as illustrated in the drawings. The part 15 is, however, separated from the head by an air gap 16 here shown as a horizontal slot cut between the side wall of the head 11 and the part 15 and running parallel to the grooves 12. The piston is provided with bosses 17 and 18 for the wrist pin. These bosses are located in alignment and diametrically opposite one another in the piston. The bosses are connected to the head by members, here shown as webs 19, 20, 21 and another like 20, but not illustrated in the drawings. These webs are parallel with the wrist pin axis and serve to make the piston stancher as well as to connect the bosses to the head. The bosses should be, and are best, connected so that the head, skirt and bosses are integral and of the same material as the bottom of the skirt. In the embodiments shown, this is accomplished by the webs 22 and 23 which are connected to the under sides of the bosses and to the inner sides of the skirt through members 24 and 25 here shown as culvert-shaped and hereinafter called culverts. The piston head is preferably strengthened by webs 26. The skirt is cut away as shown at 27 and 28 about the bosses 17 and 18 and the bosses are set within the perimeter of the piston to permit expansion along the axis of the wrist pins without binding or scoring.

The piston skirt is best made continuous below the openings 27 and 28. In the embodiments shown, strap-like members 29 and 30 connect the parts 14 and 15 at the bottom. The member 29 is slotted along the long axis

of the piston at 31 and the member 30 is slotted likewise at 32. These slits are preferably slanting to the long axis of the piston and are spanned by the culverts 24 and 25 which are 5 of resilient material. The piston skirt thrust parts 14 and 15 are connected together by members of a material having a lower co-efficient of expansion than aluminum such as 10 steel or iron, which regulate the expansion of the skirt to maintain the expansion thereof constant with the expansion of the engine cylinder, or so nearly thereto, that though there is very little clearance at the time the pistons are installed, such clearance is substantially maintained and there will be no slap, 15 no sticking and no scoring or undue wear.

In the embodiment shown, strips of the desired material are used to interconnect the parts of the skirt. These strips are anchored 20 in the parts they connect. It is convenient to use such members as A, (Fig. 4) which are best made of iron, steel or other suitable material and which consist of the lateral members 33 and 34 and the vertical members 35 25 and 36 provided with catches 37. To securely connect the members 33 and 34 to the skirt parts the vertical members 36 may be buried in the part 14, for example, by embedding them in buttresses formed on the inside wall of the part 14, thus securely anchoring the ends of the lateral members 33 and 34 in the part 14. The other ends of the members 33 and 34 are as securely anchored in the face part 15 in much the same manner. The vertical members 35 are buried in the buttresses 39 35 formed on the inner walls of the part 15 of the piston skirt. The bosses 17 and 18 and webs 19, 20 and 21 are opened at 40 and 41 and 42 and 43, respectively, to permit the passage 40 of the members 33 and 34 and to permit such members to slide slightly therein during the expansion and contraction of the skirt. As will be seen the members 33 and 34 are arranged chordally in the piston.

45 By connecting the piston skirt thrust face parts together with both iron and aluminum, we avoid slapping at the high temperatures and danger of cocking of the member 15 out of normal due to unequal heating and consequent expansion at the top and bottom of the skirt.

There will also be no danger of the member 15 cocking out of line since the more rapidly expanding aluminum steel combination at 50 the bottom will compensate for lower temperatures there. Nor will there be danger of binding at the bottom of the piston skirt when the circumference of the skirt is complete, since the slits 31 and 32 permit circumferential expansion and the resilient culverts will insure the expansion into these slits instead of outward and away from them. For while the parts 24 and 25 of the culverts expand giving the required expansion perpendicular to the wrist pin axis, circumfer-

ential expansion of the culverts will bring the culvert ends towards each other and thus tuck in the ends of the strap-like members 29 and 30 so they will not project out radially and injure the cylinder walls.

The operation is as follows: The piston is fitted with very little or almost no clearance. As the piston heats, the bosses tend to move outward, for which movement there is ample allowance. The expansion in the other direction will be from the member 14 and will be the resultant expansion of the members 33, 34, 24 and 25, and of course the expansion of the thrust faces, and these parts are so regulated that the piston walls will follow the cylinder walls with fidelity. Contraction will be in reverse of expansion.

In the embodiment shown in Figs. 5 to 8, inclusive, connectors 50 and 51 are substituted for the culverts. In this embodiment, 85 the aluminum expansion parallel to the members 33 and 34 is achieved by the bottoms 52 of the bosses 17 and 18.

It will be seen that although we make our piston of a continuous, in fact, in the embodiments illustrated, an integral piece of aluminum or the like, we do not shackle or loop the skirt with iron bands or the like, nor do we separate or isolate the parts one from the other, but employ aluminum and iron 95 parts in such arrangements that we eliminate from the pistons the faults and vices of the prior iron and aluminum pistons. The term aluminum used herein is broad enough to include aluminum alloys.

The piston is very staunch and is easily machined. The heat is effectively conducted from the head especially where the thrust face 14 joins the head. The members A are 105 relatively light and more securely anchored in the thrust walls. The explosion load is preferably taken on the face 14, which is integral with the head, and the inertia load on the face 15.

The pistons may be, and preferably are, 110 relieved as shown at 60 in Figs. 1, 3, 5 and 7 to enhance the realization of the advantages already recited herein.

While we have illustrated and described these embodiments of our invention and these particular details, we wish to be limited neither to these embodiments nor the details thereof, since many departures from both may be made without departing from the spirit of the invention.

We claim:—

1. In a piston having a skirt made of material having a relatively high co-efficient of expansion comprising thrust members, one of which is connected to the head at the periphery and separated from each other by open spaces running from near the top of the piston to near the bottom of the skirt and extending on both sides of the bosses, but leaving the continuity of the piston uninterrupted.

ed at the bottom and means of a material of a lower co-efficient of expansion than the material of the skirt bridging said open spaces and connecting said thrust members together.

5 2. In an aluminum alloy piston, a skirt having thrust members one of which is connected to the head at the periphery and being connected together at the top by steel only and at the bottom by aluminum and steel.

10 3. In a piston for internal combustion engines or the like, the combination of a head having a depending flange grooved for piston rings and a skirt, both head and skirt composed of a material having a relatively high co-efficient of expansion, said skirt having diametrically opposite thrust faces, one of which is connected to the head but the other of which is disconnected from the head by an 15 arcuate air gap, said thrust faces being separated from near the top to near the bottom of the skirt but leaving the bottom of the skirt connected for a ways up from the bottom, wrist pin bosses set within the periphery of the skirt, connecting means connecting said thrust faces together made of a material having a lower co-efficient of expansion than the skirt and extending chordally from one face to the other perpendicular or 20 substantially perpendicular to the wrist pin axis both above and below the axis, the portions of the skirt below the bosses being slotted and culvert-like members on the inside of the skirt spanning said slits.

25 35 4. In a piston, a skirt made of a material having a relatively high co-efficient of expansion and including a skirt comprising thrust face members one of which is connected to the head at the periphery and separated from near the top to near the bottom, means of a relatively low co-efficient of expansion material connecting said thrust face members, the unseparated portions of the skirt being slotted and culvert-like members spanning said slits.

40 45 5. In an aluminum alloy piston, a skirt having thrust faces, one of which is connected directly to the head and said thrust faces being connected at the top by steel alone and connected at the bottom with steel and aluminum and having pin bosses set within the perimeter of the piston, said skirt being cut away or relieved in the regions of the bosses.

50 55 6. In a piston, the combination of a head and a skirt having thrust faces made of a material having a relatively high co-efficient of expansion, one of said thrust faces being integral with the head and the other being separated from the head and connectors of a material having a lower co-efficient of expansion than the material of the skirt anchored at either end in one of said thrust faces and extending across the piston and connected to the bosses.

60 65 7. In a piston for internal combustion en-

gines or the like, the combination of a head consisting of a top and a depending cylindrical shaped flange grooved on the outside for piston rings, a skirt for the piston comprising portions having thrust faces adapted to engage the walls of the cylinder of the engine when the piston is mounted therein, said skirt being generally cylindrical in shape and said skirt and head being made of a material having a relatively high co-efficient of expansion, 70 diametrically oppositely placed wrist pin bosses mounted in said skirt and having their outer ends within the periphery of the skirt, means connecting said wrist pin bosses with the head, the skirt being relieved or cut away 75 about the bosses from the lower part of the head to below the bosses and leaving the lower portion of the piston connected together circumferentially, the lower portions of the pistons being slit below the bosses, culvert-shaped members of the same material as the skirt mounted within the piston and spanning said slits, one of said thrust face portions of the piston being integral with the head and the diametrically opposite thrust face portion 80 being disconnected from the head by an arcuate slot at the top of said thrust face portion, connectors made of a material of a relatively lower co-efficient of expansion than the material of the piston anchored at either end in 85 the thrust faces and passing through the bosses in the central portions thereof, one of said connectors being located above and one below each boss and each extending on a chord across the interior of the piston and 90 perpendicular or substantially perpendicular to the wrist pin axis.

8. In a piston, the combination of a pair of diametrically opposite thrust face members of high expandible material one of which is connected to the head at the periphery, wrist pin bosses and connectors of low expandible material slidably mounted in said bosses and connecting said face members together.

9. In a piston for internal combustion engines, the combination of a head and skirt composed of a plurality of parts, one of which is attached to and another of which is detached from the head and a tie slidably mounted in the piston interconnecting said parts.

10. In a piston for internal combustion engines, the combination of a head and a skirt comprising two thrust face portions, one of which is connected to the head and the other of which is disconnected from the head at the top, means in said piston intermediate said portions and interconnecting ties joining said portions and having bearings in said intermediate means in which such interconnecting means may reciprocate.

11. In a piston for an internal combustion engine, the combination of a head and a skirt comprising two thrust face portions, one of which is integral with the head and the other

of which is disconnected from the head by a slot at the top, said portions being separated part way along, interconnecting means for joining said portions together and wrist pin bosses provided with openings through which said interconnecting means may move back and forth.

12. In a piston for an internal combustion engine, the combination of a head and a skirt comprising two thrust face portions, one of which is integral with the head and the other of which is disconnected from the head by an air gap, said portions being separated part way and slotted the rest of the way with bridges connecting them across the slits, and interconnecting means joining the thrust face portions over the separated parts, composed of a material having a lower co-efficient of expansion than the material of the piston and intermediate members including wrist pin bosses provided with openings through which said interconnecting means may reciprocate.

13. In a piston, the combination of a pair of diametrically opposite thrust face members of high expandable material, wrist pin bosses and connectors of low expandable material slidably mounted in said bosses and connecting said face members together.

14. In a piston for internal combustion engines, the combination of a head and skirt composed of a plurality of parts, one of which is detached from the head and means slidably mounted in the piston interconnecting said parts.

15. In a piston for internal combustion engines, the combination of a head and a skirt comprising two thrust face portions, means in said piston intermediate said portions and interconnecting means tying said portions together and having bearings in said intermediate means in which such interconnecting means may move back and forth.

16. In a piston for an internal combustion engine, the combination of a head and a skirt comprising two thrust face portions, said portions being separated part way along, interconnecting means for joining said portions together and wrist pin bosses provided with openings through which said interconnecting means may move back and forth.

17. In a piston for an internal combustion engine, the combination of a head and a skirt comprising two thrust face portions, said portions being separated part way and slotted the rest of the way with bridges connecting them across the slits, and interconnecting means joining the thrust face portions over the separated parts, composed of a material having a lower co-efficient of expansion than the material of the piston and intermediate members including wrist pin bosses provided with openings through which said interconnecting means may move back and forth.

18. In a piston for an internal combustion engine, the combination of a head and a

skirt comprising two thrust face portions, one of which is separated from the head, said portions being separated part way along, interconnecting means for joining said portions together and wrist pin bosses provided with openings through which said interconnecting means may move back and forth.

19. In a piston for an internal combustion engine, the combination of a head and skirt including spaced thrust face portions, the explosion thrust face portion being connected to the head and the compression thrust face portion being disconnected from the head, wrist pin bosses and means including metals of different coefficients of heat expansion connecting the bosses to the thrust faces so as to resist the relative expansion and contraction between the faces and the wrist pin bosses.

20. In a piston for an internal combustion engine, the combination of a head and skirt including thrust face portions, one of which is connected to the head and one of which is separated from the head, means of a lower co-efficient of heat expansion than the material of the piston tying said thrust faces together, and means of the same material as the piston joining said thrust faces together, said piston being relieved on the periphery between the thrust faces.

21. In an aluminum alloy piston, the combination of a head, a skirt having thrust members one of which is connected to the head at the periphery, steel means constituting the sole connection between the top part of the thrust members and steel and yieldable aluminum members connecting the bottom part of the thrust members together, piston pin bosses and means connecting the bosses to the bottom part of the skirt.

In testimony whereof we hereunto affix our signatures this 28th day of December, 1925.

JAMES COOPER.
